CLAIM

The ornamental design for a packaging container for frozen aquarium foods, as shown and described.

DESCRIPTION

FIG. 1 is a top perspective view of a packaging container for frozen aquarium foods embodying my new design;

FIG. 2 is a top plan view;

FIG. 3 is a side elevational view;

FIG. 4 is an end elevational view;

FIG. 5 is a bottom plan view on a reduced scale; and FIG. 6 is a top perspective view showing a modified form of my new design.
